UNITED STATES PATENT OFFICE

2,514,468

INTERNAL FIN FOR HEAT-EXCHANGER
TUBESHoward F. Brinen, Racine, Wis., assignor to
Young Radiator Company, Racine, Wis., a cor-
poration of Wisconsin

Application November 5, 1947, Serial No. 784,265

4 Claims. (Cl. 138—38)

1

Increasingly, modern industry is enlarging power-generating units, particularly for automotive equipment. The development of Diesel electric locomotives, Diesel engines for aircraft, and gas-burning turbines exemplifies this trend.

The enlargement of these power-generating units presents a problem of adequately dispersing heat from the large quantities of oil required for lubricating these mammoth and heat-creating units. Generally this heat dispersion must be effected by flowing the lubricating oil through heat-exchange devices comprising batteries of tubes, usually closely assembled and associated with external fins.

In the construction of such heat-exchange devices three ends are sought. First, the highest possible transference of heat from the fluid to the metal of the tube; secondly, the passage of the fluid through the tube with the minimum of turbulence so as to present the least possible resistance to the flow of fluid through the tube; and thirdly, the prevention, insofar as possible, of the accumulation of sludge and the consequent clogging of the tube.

It is well known that the use of fins within tubes materially increases the heat transference. However, with the internal fins heretofore provided, the resulting turbulence in the fluid often is so great that the increased resistance to fluid flow completely negatives the gain in heat transference. Moreover, many of the prior fin designs present obstructions about which sludge tends to accumulate, too often resulting in a clogging if not a closing of the tube.

There is the further problem of providing a fin that can be inserted into a tube of any material length without causing the fin to buckle and thereby precluding the use of fins with tubes of any material length.

Because of these facts manufacturers of heat-exchange equipment of the tubular type have often had to choose between gaining increased heat dispersion, at the sacrifice of free fluid flow, or having a freer fluid flow with a reduction in heat dispersion.

Flat or elliptical tubes are known to provide a higher degree of dissipation than circular tubes of the same volumetric capacity. Nevertheless, these foregoing problems are as acute with flat or elliptical tubes as with circular ones.

The main objects of this invention, therefore, are to provide an improved form of internal fins, for heat-exchanger tubes, which secure a high degree of heat transference with a minimum resistance to fluid flow through the tube, and which

2

occasions the very least likelihood of sludge accumulation; to provide an improved internal fin of this kind which may be inserted into a tube of considerable length without buckling; to provide an improved fin of this kind which when inserted retains itself in place without the necessity of being bonded to the tube; and to provide an improved internal fin of this kind particularly adapted for use with flat or elliptical-shaped tubes.

In the accompanying drawings,

Fig. 1 is a perspective view of a section of a flat or elliptical-shaped tube wherewith is associated an internal fin embodying this invention;

15 Fig. 2 is a plan view of a fragment of the improved fin removed from the tube;

Fig. 3 is a fragmentary and partly cross-sectional view of a tube of the type with which this improved fin is particularly suited for use;

20 Fig. 4 is an enlarged, transverse, cross-sectional view of the tube-fin assembly, taken on the line 4—4 of Fig. 1; and

Fig. 5 is an end view of the tube-fin assembly shown in Fig. 1.

25 A tube 6, for use with which this improved form of internal fin 7 has been designed, is one of the types of tube quite generally used in the construction of heat-exchanger cores for the dispersion of heat from the lubricating oil used

30 in heat-creating, power-generating units. As noted, this is a seamless tube redrawn to the form shown from a circular tube produced by the well-known "bench drawing" process. The tube could be of the seam type wherein a flat piece of

35 thin sheet metal is folded and the abutting edges are bent and interlocked and subsequently bonded to form a fluid-tight joint.

The fin 7, embodying this invention, is of comparatively thin construction. In its preferred

40 form, for use within a tube, it is bent along its longitudinal median to form a central or median ridge 8 and is also bent longitudinally along the lines 9 and 10 intermediate the ridge 8 and the lateral edges 11 and 12 so as to form the angularly-disposed border portions 13 and 14. These border portions are preferably approximately

45 parallel to the respective portions of the strip which form the median ridge 8.

Although the ridge 8 is herein shown in the

50 form of a V, some other geometric form might be effected.

This arrangement of bends to form the median ridge 8 and the angularly-disposed border portions 13 and 14 disposes the intermediate portions 15 and 16 in a common plane approximately

equi-distant between a plane passing through the lateral edges 11 and 12 of the angularly-disposed border portions 13 and 14 and the apex 17 of the median ridge 8.

A strip from which a fin of this type is formed, prior to its bending, is made of a width such that after the bends have been formed the distance between the lateral edges 11 and 12 of the border portion 13 and 14 will be slightly less than the major transverse dimension of the tube 6.

Being made of resilient or spring-like material the fin may be inserted into the tube so that it will contact the tube 6 along the lateral edges 11 and 12 and the apex 17 (as indicated in Figs. 4 and 5) and will be frictionally held in place by the resiliency of the fin itself. Therefore, there is no need for bonding the fin to the tube either to retain it in place or to secure appropriate contact of the fin with the tube as above indicated. Moreover, being capable of yielding between these three points of contact with the tube, a fin of considerable length, in fact several feet, may be inserted into a tube of equal length very easily with no danger whatever of the fin buckling.

Although not imperative by any means, for certain uses the fin will have apertures 18 punched in the portions 15 and 16. Such apertures will permit the fluid on either side of the fin to contact the fluid on the opposite side throughout the length of the tube. This will ensure having the temperature of the fluid throughout the length of the tube practically uniform.

Although the use of such apertures may cause a slight amount of turbulence the other gains in the use of such an internal fin are such as to make that slight turbulence rather negligible.

Laboratory tests with a fin construction of this kind show an increase of approximately 22 per cent in heat transference over that obtained with the same core without the internal fin. Also these tests show that this gain in heat dissipation is obtained with only one third of the pressure drop which results from the use of other types of internal fins.

Other variations and modifications in the details of structure and arrangement of the parts may be resorted to within the spirit and coverage of the appended claims.

I claim:

1. An internal fin for heat-exchange tubes in the form of an elongated strip bent along a longitudinal median to form a ridge and bent longitudinally intermediate said median ridge and the respective lateral edges so as to angularly dispose the border portions of said strip approximately parallel to the respective portions of said strip which form the median ridge whereby said strip upon insertion into a tube is frictionally retained in place by the three-point contact of the lateral edges of said strip and the apex of the median bend against the walls of said tube.

2. An internal fin for heat-exchange tubes in the form of an elongated strip bent along a longitudinal median to form a ridge and bent longitudinally intermediate said median ridge and the respective lateral edges so as to angularly dispose the border portions of said strip approximately parallel to the respective portions of said strip which form the median ridge, the bends in said strip being so formed that said angularly-disposed border portions and the respective sides of said median ridge are disposed in substantially parallel planes and the portions of said strip between said border portions and median ridge portions are disposed in a plane equidistant between the plane of the lateral edges of said strip and the apex of said median ridge, whereby said strip upon insertion into a tube is frictionally retained in place by the three-point contact of the lateral edges of said strip and the apex of the median bend against the walls of said tube.

3. An internal fin for heat-exchange tubes in the form of an elongated strip bent along a longitudinal median to form a V-shaped ridge and bent longitudinally intermediate said median ridge and the respective lateral edges so as to angularly dispose the border portions of said strip approximately parallel to the respective portions of said strip which form the median ridge whereby said strip upon insertion into a tube is frictionally retained in place by the three-point contact of the lateral edges of said strip and the apex of the median bend against the walls of said tube.

4. The combination of a flat heat-exchanger tube and an internal fin, said fin being in the form of an elongated strip bent along a longitudinal median so as to form a V-shaped ridge and bent longitudinally intermediate said median ridge and the respective lateral edges so as to angularly dispose the border portions of said strip approximately parallel to the respective portions of said strip which form said median ridge and having the portions of said strip between said border portions and said median ridge disposed intermediate the plane of the lateral edges of said strip and the apex of said V-shaped median ridge, whereby the lateral edges of said strip and the apex of said median ridge contact the opposite walls of said tube and frictionally hold said fin in said tube.

HOWARD F. BRINEN.
